UNITED STATES PATENT OFFICE.

JOHN A. WITMAN, OF COLUMBUS, OHIO.

DESIGN FOR A GAS HEATING-STOVE.

SPECIFICATION forming part of Design No. 35,629, dated January 28, 1902.

Application filed December 26, 1901. Serial No. 87,371. Term of patent 3½ years.

To all whom it may concern:

Be it known that I, JOHN A. WITMAN, a citizen of the United States, residing at Columbus, in the county of Franklin and State of Ohio, have invented and produced a new and original Design for Gas Heating-Stoves, of which the following is a specification, reference being had to the accompanying drawing, forming part thereof.

10 The drawing referred to shows my newly-designed stove in perspective.

As shown in the drawing, the leading or material features of my design consist in the upper and lower relief ornaments *a* and *b*, arranged on the front face of the stove-body and at the corners thereof, the upper ornaments *a* each consisting of an elongated scroll-like body having somewhat the form of a figure 8. The top of the stove-face inclines 15 from its center toward the ornamented corners, and from the apex of the angle thus produced depends in relief a center ornament *c*, on the face of which are raised opposing scrolls. Each of the lower corner ornaments

b is in the nature of a raised or relief body 25 arranged vertically and having opposing leaf-scrolls. On the center or face of the stove-fender is provided in relief an ornament *d*, comprising a crossed torch and quiver of arrows, which at their intersection also intersect the central portion of a horizontally-arranged bow, the ends of the latter being connected by ribbons and the upper and lower angles between the crossed quiver and torch being filled with flowers and leaves, as shown. 35

Having described my invention, what I claim as new, and desire to secure by Letters Patent, is—

The design for a gas heating-stove, as herein shown and described. 40

In testimony whereof I have signed my name to this specification in the presence of two subscribing witnesses.

JOHN A. WITMAN.

In presence of—

C. C. SHEPHERD,
J. E. WITMAN.
